JAMES H. OLD, OF FOREST PARK, ILLINOIS, ASSIGNOR OF ONE-HALF TO JULIUS J. OHLIS,
OF CHICAGO, ILLINOIS

FLOOR LIGHT, VAULT LIGHT, AND ROOF LIGHT CONSTRUCTION

Application filed April 2, 1931. Serial No. 527,283.

This invention relates to those structures in which floor lights, roof lights or vault lights are carried by a supporting structure in such manner as to form a light transmitting floor, roof, vault ceiling or pavement. Structures of this kind must have sufficient strength so as to support heavy weights and so that they may be used as surfaces upon which people may walk with entire safety.

It is also a desideratum that there shall be a relatively great area of glass and that the structure shall have as little weight as possible with, however, the requisite strength.

It has heretofore been the practice in this art to surround the lights which are usually square with concrete or metal or other hard substance and all these materials have caused trouble due to the breakage of the glasses, leakage, and disintegration of the substance surrounding the lights.

Furthermore, it has been attempted to use relatively large panes of glass set on parallel carrying bars and this type of construction cannot be erected in a horizontal or near horizontal position as it is subjected to leakage and breakage of glass due to expansion and contraction and vibration, nor can such a structure be walked upon with safety.

Furthermore in these structures of the character described, condensation is at a maximum due to the fact that the substance which surrounds and is disposed between the glasses has heretofore been of such a nature as to be a conductor of heat and cold from the outside to the under side of the glass and in constructions using large panes of glass set on parallel carrying bars, condensation is at a maximum due to the thin glass and the carrying bars being exposed to the outside surface which act as conductors of heat and cold. Furthermore, in constructions known to me and used in the prior art, considerable trouble has been caused by buckling or arching due to the unequal expansion and contraction of the fabricated steel bars or of the reinforced concrete frame which is not so designed as to have the same area in all directions.

The general object of the present invention is to provide a structure of this character

which can be erected in a near horizontal position, which can be walked upon with greater safety than constructions of the prior art, which can be cheaply manufactured and fabricated and erected in a very simple manner and which will have a greater glass area of less weight per square foot than prior constructions.

A further object is to provide a structure of this character which will eliminate condensation, which can be manufactured from sheet metal, fabricated in such manner as to eliminate the necessity of using additional reinforcing or carrying members or intermediate structural supports as required with cast iron, steel bars, reinforced concrete and other such metal constructions.

A further object is to so form the sheet metal elements which support the lights that the necessity of welding, soldering or caulking is eliminated.

A further object is to provide for the use of a tar and sulphur composition surrounding each pane and disposed between the panes and provide means which will act as a key to lock the tar and sulphur sealing compound in place and thus prevent this compound becoming displaced and the glasses from coming loose.

Other objects will appear in the course of the following description.

My invention is illustrated in the accompanying drawings, wherein:

Figure 1 is a top plan view partly broken away of a vault light, skylight, or floor light constructed in accordance with my invention;

Figure 2 is a section on the line 2—2 of Figure 1;

Figure 3 is a section on the line 3—3 of Figure 1;

Figure 4 is a fragmentary perspective view of the supporting elements at their junction;

Figure 5 is a fragmentary perspective view of one of the elements B showing the tongues projecting therefrom;

Figure 6 is a fragmentary longitudinal sectional view through one of the longitudinal elements and a transverse element showing the means for holding the elements together.

Referring to these drawings, A and B designate what may be termed the longitudinal and transverse fabricated sheet metal supporting elements. The members A may be considered to be the main supporting elements, these members being substantially parallel to each other while the members B may be considered as the transverse or cross elements fitting into and interlocking with the main supporting elements A and defining openings conforming to the contour of the glass panes. The longitudinal elements A are formed each of a single piece of sheet metal longitudinally bent at its middle at 10, the middle being extended in parallel relation as at 11, then the two sides of the sheet being bent laterally outwardly as at 12, then upwardly as at 13 and then downwardly as at 14, then parallel to and in close relation to the portion 12 as at 15 and then bent upwardly as at 16, the two portions 16 being in slightly divergent relation to each other and constituting a key as will be later stated. Disposed between the two side portions 11 of the element A is a core bar designated 17, this core bar spacing the lateral portions 11 of the bar A apart and giving strength to the element A. The transverse elements B are constructed, generally speaking, of the same form as the elements A and have the same height, and, therefore, the same reference numerals are used to indicate like portions of the elements A and B. The elements B, however, have their portions 11 flanged outwardly at the ends, these flanges being designated 18. The element B also differs from the element A in that the portions 11 midway between the lower end of the element B and the outwardly extending flanges 12 are deflected to form a square passage 19 through which a tie bar 20 may pass. Furthermore, these lateral flanges 12 are cut away at 21 to accommodate the laterally flanged portions 12 and 13 of element A and the portions 12 are formed to provide tongues 22 at the ends of the elements B which engage in slots 23 formed between the portions 12 and 15. It will be seen that the bolts 20 extend through the passages 19 and through the webs 11 of the elements A and these bolts are provided with nuts 24 on their opposite ends whereby the elements B are held in conjunction with the elements A. Obviously if desirable, the flanges 18 may be riveted to the webs 11 of the elements A. The bolts 20 and the tongues 22 hold the elements A and B in interlocked relation to each other and define rectangular openings having seats formed by the portions 12, 13 and 14 for the edges of the lights. The lights or glass panes are designated 25. These are made of relatively thick glass having downwardly extending flanges 26 at their margins so as to fit down between the

portions 14 and the portions 16 of the elements A and B.

Preferably insulating members 27 angular in cross section and preferably formed of cork are disposed beneath the lower edges of the flanges 26 and extend upwardly between the inside faces of these flanges and the portions 14.

The flanges 16 extend up between the perimeters of the lights 25 and the space between the side edges of these lights is filled with a sealing compound 28 preferably of tar and sulphur. This sealing compound is filled up to a level and flush with the upper faces of the lights 25. The side edges of the lights are grooved or otherwise undercut at 29 so that the tar and sulphur compound may interlock with the side edges of the lights and this compound 28 is also anchored in place by the flanges 16 which constitute keys or anchors by reason of their divergent relation to each other. Thus the compound 28 is held firmly in place against detachment and the lights 25 are held firmly in place. The under side of the lights, which lights are preferably formed of pressed glass, are so shaped as to provide four planes pitching from the center in four directions to the outer wall of the glass, these planes being designated 30. This will drain off any condensation which might form on the under faces of the glass. This small amount of condensation will be carried off from the under side of the glass on to the seats formed by the portions 14 and 15 of the elements A and B and will there evaporate. These seats, therefore, not only constitute seats, but gutters to receive any small amount of condensation which may form on the under side of the lights.

In placing the structure in position, the grids or frames formed of the elements A and B, after these elements are assembled, are laid in place over the openings to be covered, the glasses or lights are then set in place and sealed weathertight with the tar and sulphur sealing compound. This sealing compound is mixed at the factory and shipped to the site of erection in the form of cakes. These are broken up and melted and poured in and around the glasses, thus eliminating the necessity of depending on the human element to mix any materials at the site of erection. The erection of this construction is particularly simplified by the fact that there are only three operations necessary, namely the setting of the grids or frames, the setting of the lights and the pouring of the sealing compound in and around the glasses.

My improved construction is so relatively simple and light that a greater number of square feet can be readily erected in given time than is possible in the erection of any other vault light, floor light, skylight or roof light known to me. The use of sheet metal,

prefomed shapes, eliminates the necessity of using cast iron, fabricated steel bars or reinforced concrete. These shapes or elements A and B are light and, therefore, may 5 be more readily shipped and handled than cast iron or fabricated steel bars.

The elements A and B obviously may be made of various sheet metals and various gauges and with various finishes. Thus 10 coated sheet steel, zinc coated sheet steel or rust resisting steel sheets can be used and the finished grid or frame can be galvanized; painted or enameled. A structure of this character can be erected in a near horizontal 15 position and remain water-tight, can be walked upon, and support relatively heavy loads. The sheet metal elements A and B can be formed without the use of welding, soldering or caulking and without using 20 fabricated steel bars. Furthermore, in my structure, no metal is exposed on the top surface, but the top surface is composed solely of glass with a narrow margin of tar and sulphur compound surrounding the glass and in 25 between each light and thus 90 or more per cent of glass area is obtained.

As no metal is exposed at the top surface of this construction, condensation is at a minimum inasmuch as there is no metal to act as a 30 conductor and transmit the cold of the sheet metal elements A and B below. Condensation is further reduced to a minimum due to the fact that the cork gasket or cushion 27 is used as an insulation between the glasses and 35 the sheet metal formed shapes. This cork insulation 27 is firmly cemented with waterproof liquid cement to the seats formed by the portions 14 and 15 and the under edge of the flange 26 which extends downward from 40 the four side margins of each light is grooved at 26a to provide eight small feet, thus securing a minimum of glass surface in contact with the cork insulation. These eight feet which are one-eighth of an inch in height al- 45 low the tar and sulphur compound to run under each four sides of the glass, thereby aiding this insulation. It will be seen that at no place does the glass come in direct contact with any part of the sheet metal form- 50 ing the elements A or B.

It is also to be noted in this connection that the lights 25 at their margins are deeper than the depth of the seats so that under faces of the glass do not come in contact with the two 55 ply flanges (13 and 14) which form the lateral flange of the seat. It is also to be noted that because of the bends given to the sheet metal and the fact that each sheet metal element is two ply throughout its entire extent, 60 the elements A and B are particularly rigid. Furthermore, the supporting ability of the two-ply flanges which form the seats for the glass is aided by the anchoring flanges 16 which extend up into the binding material so 65 that downward pressure on the lights which

would tend to bend downward the seats for the lights is resisted by these upwardly extending anchoring tongues or flanges 16 bearing against the binding material 28 which in turn is held from lateral movement by the 70 flanges 26 of the lights.

It is also to be particularly noted that the cross members B have practically the same cross sectional area and the same specified depth as the members A. Therefore, when the expansion and contraction takes place, this expansion and contraction will be equal throughout the entire structure. Where this is not the case and the cross members of a grid have a different depth and a different 75 cross sectional area from the longitudinal members, there will be unequal expansion and contraction which will buckle or arch the construction. This causes breakage of glass and 80 disruption of the entire construction. 85

This grid or frame will be preferably made up at the factory from the units A and B but obviously it might be made up at the site of the building, the longitudinal elements and the transverse elements being previously cut 90 or formed to the proper sizes, for the work to be done.

I claim:—

1. In a vault light, sky light, or floor light structure, longitudinal and transverse supporting elements defining rectangular openings, each element having two parallel seats defined by laterally and upwardly extending flanges, the lights having downwardly extending marginal flanges operatively supported on the seats, and binding material disposed in the spaces between the side edges of the lights, the supporting elements being formed to provide anchoring members extending divergently upward into the binding 100 material but terminating short of the upper surface of the binding material and the lights. 105

2. In a vault light, sky light or floor light structure, longitudinal and transverse supporting elements defining rectangular openings, each element having two parallel seats defined by upwardly extending lateral flanges, lights having downwardly extending marginal flanges extending downward into said seats, insulating members angular in cross section and disposed within said seats between the inner faces of said flanges and the inner faces of the seats and the flanges of the lights and directly supporting the flanges of the lights, binding material disposed in the spaces between the side edges of the lights and extending downward to said insulating members, the supporting elements being formed to provide anchors extending upward into the binding material. 115 120

3. A vault light, sky light and floor light structure including longitudinal and transverse supporting elements defining rectangular openings, each supporting element being formed of sheet metal bent to provide a two- 130

- ply vertical web, the metal at the upper margin of the web being bent outward in opposite directions, then upward, then inward and downward in a vertical plane to form a seat, 5 lights having marginal flanges extending downward into the seat, and binding material filling the spaces between the margins of the lights and anchored thereto.
4. A vault light, sky light and floor light 10 structure including longitudinal and transverse supporting elements defining rectangular openings, the elements being formed of sheet metal, both sets of elements being alike in cross-sectional area and form, each of said 15 elements being formed of sheet metal bent to form a two-ply vertically extending web, the metal at the upper margin of the web being bent out in opposite directions, then upward, then inward and downward in a 20 horizontal plane, then horizontally inward to form a seat, the metal then being extended upward, lights having marginal flanges extending downward into the seats, and binding material filling the spaces between the 25 margins of the lights and anchored thereto by the upwardly extending portions of said elements disposed between the margins of the lights.
5. A vault light, sky light or floor light 30 structure including longitudinal and transverse supporting elements defining rectangular openings, each element being formed of sheet metal bent to form a two-ply vertically extending web, the metal at the upper margin 35 of the web being bent outwardly in opposite directions to form light supporting seats, a core bar disposed between the two plies of the vertical web, lights resting on said seats and binding material disposed between the 40 margins of the lights and anchored to said elements.
6. A vault light, sky light or floor light 45 structure including longitudinal and transverse supporting elements defining rectangular openings, each element being formed of sheet metal, bent to provide a two-ply vertical web, the metal at the upper margin of the web being bent outward in opposite directions, then upward and then inward and 50 downward in a vertical plane to thus provide light seats, lights having marginal flanges extending downward into the seats, the under faces of the flanges being transversely grooved at intervals, and binding material 55 filling the spaces between the margins of the lights and extending through said grooves, and means anchoring the binding material to the elements.
7. A vault light, sky light or floor light 60 structure including longitudinal and transverse supporting elements of folded sheet metal defining rectangular light receiving openings, the transverse elements having substantially the same cross sectional form 65 and cross sectional area as the longitudinal elements, the elements being formed to provide light receiving seats, said transverse elements abutting against the longitudinal elements and being interlocked therewith, lights disposed in said openings and resting on the 70 seats, and binding material disposed between the lights and having its upper surface flush therewith.
8. A vault light, sky light or floor light 75 structure including longitudinal and transverse supporting elements defining rectangular openings, each transverse element having substantially the same cross sectional form and cross sectional area as the longitudinal elements, both of said elements being formed to provide seats, each transverse element at its ends having laterally extending flanges abutting against the vertical faces of the longitudinal elements, the transverse elements having horizontally disposed 80 tongues projecting from the ends thereof, the longitudinal elements having slots to receive 85 said tongues.
9. A vault light, sky light or floor light 90 structure including longitudinal and transverse supporting elements of folded sheet metal defining rectangular light receiving openings, each transverse element having substantially the same cross sectional form and cross sectional area as the longitudinal 95 elements, all of said elements being formed to provide light receiving seats, the transverse elements abutting at their ends against the longitudinal elements, bolts passing longitudinally through the transverse elements 100 and engaged with and extending through the longitudinal elements.
10. A vault light, sky light and floor light 105 structure including longitudinal and transverse supporting elements of folded sheet metal bent to form a two-ply vertical web, the transverse elements having substantially the same cross sectional form and cross sectional area as the longitudinal elements, all of said elements being formed to provide 110 light receiving seats, the transverse elements abutting against the webs of the longitudinal elements, each traverse element having the two plies of its web bent outward away from each other to form a bolt passage extending longitudinally through the web, and a bolt extending through said passage and through the webs of the adjacent longitudinal elements and having nuts engaging against said webs to thereby lock the transverse elements to the longitudinal elements, and lights supported in said openings by 115 said longitudinal and transverse elements.
11. A vault light, sky light and floor light 120 structure including longitudinal and transverse supporting elements of folded sheet metal, the sheet metal of each of said elements being bent to form a two-ply vertical web and laterally disposed light receiving seats at the upper end of the web, the 125

webs of the transverse elements having laterally extending wings at their ends abutting against the webs of the longitudinal elements, the two ply webs of each transverse element being bent to form a bolt passage, a bolt extending through said passage and through the vertical webs of the longitudinal elements and having nuts bearing against said webs, the light-receiving seats of the transverse elements being cut away at their intersection with the seats of the longitudinal elements, the transverse elements having tongues extending outward in the same plane as the seats therein, the longitudinal elements being slotted to receive said tongues.

12. A vault light, sky light or floor light structure including longitudinal and transverse supporting elements defining rectangular openings, each supporting element being formed of sheet metal bent to provide a two-ply vertical web, the metal at the upper margin of the web being bent outward in opposite directions, then upward, then inward and downward in a vertical plane, then horizontally inward to form a seat and then upward, the opposed webs of each transverse element being bent outward to form a bolt passage, a bolt extending through the passage and through the vertical webs of the longitudinal element, each transverse element at its opposite ends on a level with the seats being formed with longitudinally extending tongues, each longitudinal element being slotted just below the seats to receive said tongues of the transverse elements, lights

having downwardly extending flanges disposed in said seats, initially plastic binding material disposed between the confronting edges of the lights and extending down and around the last named upwardly extending portions of the elements whereby the binding material will be anchored to the elements.

13. In a vault light, sky light or floor light structure, longitudinal and transverse supporting elements defining rectangular openings, each element having two parallel seats defined by upwardly extending lateral flanges, the transverse elements being interlocked with the longitudinal elements and having substantially the same cross sectional area and the same cross sectional form as the longitudinal elements, insulating members resting upon said seats, lights having downwardly extending marginal flanges extending downward into said seats and resting upon the insulating elements, said flanges having a depth greater than the seats and less in width than the seats whereby the under surface of any light is disposed above the upper edge of the flange defining the seat, the undersurface of each light being formed with downwardly and outwardly inclined faces whereby water of condensation will run down to said seats, an initially plastic filling material disposed between the edges of the lights and extending downward below the lower edges of the flanges of the lights and anchored to said elements.

In testimony whereof I affix my signature.
